UNITED STATES PATENT OFFICE.

JOHN F. O'CONNOR, OF CHICAGO, ILLINOIS, ASSIGNOR TO WILLIAM H. MINER, OF CHAZY, NEW YORK.

BODY-BOLSTER SIDE BEARING.

1,357,808.

Specification of Letters Patent.

Patented Nov. 2, 1920.

Application filed September 5, 1919. Serial No. 321,754.

To all whom it may concern:

Be it known that I, JOHN F. O'CONNOR, a citizen of the United States, residing at Chicago, in the county of Cook and State 5 of Illinois, have invented a certain new and useful Improvement in Body-Bolster Side Bearings, of which the following is a full, clear, concise, and exact description, reference being had to the accompanying drawings, forming a part of this specification.

This invention relates to improvements in body bolster side bearings.

The object of the invention is to provide a simple and relatively inexpensive, gravity controlled, self-centering side bearing especially adapted for attachment to body bolsters of railway cars.

In the drawing forming a part of this specification, Figure 1 is a vertical sectional view taken through the body and truck bolsters of a car and showing my improvements in connection therewith. Fig. 2 is a top plan view of the side bearing proper, parts being broken away to accommodate the figure on the sheet. And Fig. 3 is a vertical sectional view taken substantially on the line 3—3 of Fig. 1.

In said drawing 10 denotes the upper portion of a truck bolster and 11 the under side of a body bolster of a railway car arranged in the relation normally obtaining on a car. I have shown my improved side bearing as attached to the under side of the body bolster 11, and, as shown the same comprises, broadly, a housing or retaining casting A, an anti-friction element B, a block C, a retaining wear plate D, and a pair of disks E—E.

The retaining member A, as shown, is of substantially box form and has depending end walls 12—12, elongated depending side walls 13—13, and perforated corner lugs or ears 14—14 by which it is adapted to be riveted or otherwise rigidly secured to the bolster.

The side walls 13 are provided on the inner faces thereof with recesses of special form. Each of these recesses at its lower end is curved so as to form an inwardly extending flange as indicated at 15 in Fig. 1. Said flanges 15 form the supports or ledges for the disks E, hereinafter described. Approximately the upper one-half of each of said recesses is formed with a slight flare as indicated at 16 and at the top portion

with straight side edges indicated at 17. These portions of the said recesses form guiding and centering means for the anti-friction element B, as hereinafter described.

Said anti-friction element B is in the form of a combined roller and rocker and has an enlarged lower end provided with a rounded bearing surface indicated at 18 which is adapted to engage the truck bolster or any suitable wear plate thereon. At its upper end, the element B is provided with another rounded bearing surface indicated at 19, said surfaces 19 and 18 being made concentric although preferably of different radii. Said bearing surface 19 is normally spaced a slight distance below the under surface of the plate D. The latter may be made of case hardened steel or other suitable wear resisting metal and is preferably inserted through slots 20 in the end walls of the retaining member A. Said plate D supports the block C as clearly indicated in Figs. 1 and 3 and in order to prevent accidental removal of the plate D, said block C is notched on its end edges as indicated at 21—21 to accommodate cotters 22 which are inserted in the plate D. This arrangement is most clearly shown in Fig. 2 upon which it will be evident that the plate D cannot be moved horizontally accidentally.

The anti-friction element B on each side thereof at the top, is provided with lugs 23—23, the same being laterally extended and working within the recesses formed on the inner faces of the side walls 13 of the member A. Said lugs 23 are of special form and each has a rounded lower end or fulcrum point as indicated at 24 in Fig. 1. From the rounded end, the edges extend upwardly at an incline as indicated at 25—25 on each side thereof until the dimension crosswise of the lug approximates closely the distance between the edges 16—16, defining the recesses. Above this point, the edges of the lugs 23 are rounded and converge slightly as indicated at 26—26. Across the top, the edges of the lugs 23 are also rounded on a long radius as indicated at 27. It will be noted that said upper edges 27 are spaced from the under side of the bolster a distance slightly greater than the distance between the bearing surface 19 and the plate D.

Each of the disks E is of oval form in general outline and has a lower rounded

edge 28 and an upper rounded edge 29. The radius of the lower rounded edge 28 is made less than the radius of the supporting ledge or flange 15 so that the disks E are free to rock back and forth on the supporting ledges 15. The rounded ends or fulcrum points 24 of the lugs 23 are normally supported by the disks E as indicated by the full lines in Fig. 1.

10 The operation is as follows: Assuming the parts in a normal position as shown in full lines in Fig. 1, when the two bolsters approach each other and relative movement therebetween occurs radially, the anti-friction element B will of course be swung to one side or the other. In the first instance said element B will be elevated so as to remove the weight thereof from the disks E and transfer the pressure from the bearing surface 19 to the plate D. As the element B swings or rolls on the bearing surface 19, as for instance to the position shown by the dotted lines in Fig. 1, the lugs 23 will move within their corresponding guides to the position indicated by the dotted lines in Fig. 1. The configuration of the lugs 23 is such that the distance at any time between the edges of said lugs and adjacent portions of the guideway will remain substantially constant. A limit to the rolling movement of the element B will obtain when the latter engages the lower edge of the corresponding end wall 12 as indicated in Fig. 1 and this will occur, preferably, when the corresponding plain edges 25 of the lugs 23 lie against the guide flanges 16.

Assuming that the pressure from the anti-friction element is then removed, the latter will of course first be pulled down until the weight thereof is transmitted from the lugs 23 to the disks E. Fulcrum points are thus formed between the lugs 23 and the disks E and the element B will swing downwardly about these fulcrum points to a vertical position due to the eccentric weight of the element B. As this swinging movement takes place the disks E will be rocked or rolled toward the left, as viewed in Fig. 1 and will remain in such displaced condition so long as the weight of the anti-friction element B is sustained thereby. During this oscillating movement, it is evident that the lugs 23 and guideways therefor will insure the return of the anti-friction element to its central position because of the special formation of the lugs as hereinbefore described. When the anti-friction element B is next

brought into play it will be first elevated, which will remove the weight thereof from the disks E and thereby permit the latter to roll back to their normal central position and in readiness for effecting the return of the anti-friction element after the completion of the next actuation.

I claim:

1. In a side bearing, the combination with a supporting member adapted for attachment to a body bolster and having depending side walls and an upper bearing surface, of an anti-friction element adapted for rolling movements, and means for sustaining said element thereon, said sustaining means including disks mounted on the supporting member and adapted to roll thereon, and fulcrum projections extending from said element and adapted to be supported on said disks during the return movement of said element.

2. In a side bearing, the combination with a supporting member adapted for attachment to a body bolster and having depending side walls and an upper bearing surface, of an anti-friction element adapted for rolling movements, and means for sustaining said element thereon, said sustaining means including, oppositely arranged disks mounted in the side walls of said retaining member and adapted to roll for a limited distance with respect thereto, guideways formed on said side walls, and laterally extending lugs from said element disposed within said guideways and normally supporting said element from said disks.

3. In a side bearing adapted for application to a car body bolster, the combination with a housing adapted to be secured to the under side of said body bolster, said housing having depending side walls and an upper bearing surface, said side walls being provided with guideways on the inner faces thereof and having also lower curved supporting flanges, of ovaliform disks rockably supported on said flanges, and an anti-friction element having upper and lower bearing surfaces and provided with laterally extended lugs disposed within said guideways, said lugs having rounded lower ends arranged to act as fulcrums to support said element from said disks.

In witness that I claim the foregoing I have hereunto subscribed my name this 20th day of Aug., 1919.

JOHN F. O'CONNOR
